(57) **CLAIM**

I claim the ornamental design for wallet with adjustable attachment mechanism, as shown and described.

DESCRIPTION

FIG. 1 is a front perspective view of a wallet with adjustable attachment mechanism showing my new design;

FIG. 2 is a front elevational view thereof;

FIG. 3 is a top plan view thereof;

FIG. 4 is a rear elevational view thereof;

FIG. 5 is a bottom plan view thereof; and,

FIG. 6 is an end elevational view thereof.
